CHARLES R. OTIS AND NORTON P. OTIS, OF YONKERS, NEW YORK.

Letters Patent No. 83,725, dated November 3, 1868

IMPROVEMENT IN HOISTING-APPARATUS.

The Schedule referred to in these Letters Patent and making part of the same.

To all whom it may concern:

Be it known that we, CHARLES R. OTIS and NORTON P. OTIS, both of Yonkers, in the county of Westchester, and State of New York, have invented certain new and useful Improvements on Hoisting-Apparatus, of which the following is a full, clear, and exact description, reference being had to the accompanying drawing, which forms part of this specification, and in which—

Figures 1 and 2 represent sectional opposite side or end elevations of a hoisting-apparatus constructed according to our improvement, and

Figure 3 represents a partly sectional rear elevation or view, at right angles to fig 1. of the same.

Similar letters of reference indicate corresponding parts throughout the several figures.

The leading feature or object of our invention is the running of hoisting-apparatus at what may be termed rapid velocity, without objectionable noise—an important consideration where the same is designed for hotel-use and other purposes. To accomplish this, we employ endless screws, working in worm-wheels at opposite ends or sides of the drum, to divide or equalize wear; and the nature of our invention consists in coupling said screws or their shafts together, by means of strap or belt, and connecting the worm-wheels, which they serve to drive, with the hoisting-drum, through interposed ratchet or spring-attachments, or both, whereby the work is divided between the two screws, thus reducing strain and wear, and which, owing to the almost unavoidable slipping of the belt, and other causes, it is impracticable to attain otherwise.

Referring to the accompanying drawing, A represents the hoisting-drum, which is here supposed to be fast to its shaft, a, that is supported and works in suitable bearings, b. B is the hoisting-rope or chain, and C the pulley over which the same is passed, to connect with the platform of the apparatus.

To illustrate the different means that may be employed, either separately or concerted, in carrying out our improvement, the drum A is shown as driven at one end, through the interposition of springs, S, and at its other end through a ratchet-wheel, R, and pawl or pawls, the action of which devices is hereinafter described; but so far as the principle of operation is concerned, a spring-attachment may be substituted for the ratchet, or a ratchet-attachment for the spring.

D D' are driving-pulleys, set in motion by any suitable means, and coupled by belt or strap, G, that may be kept taut by a tightening-pulley, H. The pulleys D D' carry on their shafts c c' endless screws E E', arranged to gear with and drive worm-wheels F F', which, by means of sleeves or otherwise, are loosely hung on the drum-shaft a. The ratchet-wheel R is connected with the one worm-wheel F, and gears with the drum by or through a spring-borne pawl or pawls,

d, while the other worm-wheel, F', is connected with the drum through the springs S, carried by said wheel acting on or in connection with studs e, projecting from or made fast to the drum.

From this description it will be perceived that screws being employed as drivers, and belt and pulleys being used in the place of spur-gear to operate them, a comparatively noiseless action is secured, but, as the motion derivable from screws is naturally slow, it becomes necessary, in order to give the requisite speed to the hoisting-drum, that the pulleys which operate the screws should be rotated at a very high velocity, in accomplishing which the belt that couples said pulleys is apt, occasionally, to slip on one or other of the latter, by reason of a difference in the smoothness or biting-condition of their peripheries, or from other causes. This has the effect of throwing all the work upon the screws, but by the means we interpose to connect the worm-wheels with the drum, such effect is neutralized, and the work divided between the two screws, so as to reduce strain and wear. Thus, by the application of the springs S and ratchet-wheel R, for instance, supposing, in hoisting, the wheel F to run the fastest, then the ratchet-wheel R takes the lead in driving, causing increased compression of the springs S, which resistance is felt or transferred through the wheel F' to the screw E', that operates the latter, and thus the strain or wear is divided between the two screws, while, if the wheel F' run the fastest, the springs S take the lead in driving, and are extended, causing the ratchet-wheel R to slip the pawl or pawls d, till the action of the springs causes a division of the strain. It may be preferred to dispense with the ratchet-attachment, and employ springs at both ends, or no springs, and ratchets at both ends of the drum, in which latter case, and by a suitable disposition of the pawls, the worm-wheel that acts as a driver in hoisting will lag in lowering, and thus the wear upon the screws be divided, the one bearing the strain in hoisting, and the other in the reverse motion of the drum. It is preferable, to secure a sensitive adjustment of the interposed driving-attachments, that either one of the pulleys D D' should be slightly of larger diameter than the other.

What is here claimed as new, and desired to be secured by Letters Patent, is—

The combination, with the hoisting-drum, of screws operated through pulleys, by a belt or band coupling the same, said screws gearing with worm-wheels arranged at opposite ends of the drum, and connected with the latter by interposed spring and ratchet-attachments, or either, substantially as specified.

CHAS. R. OTIS.
